FIRE TRUCK

Michael Dennis Callahan, 17011 Dover Lane,
Independence, Mo. 64056

Filed Apr. 10, 1970, Ser. No. 22,369

Term of patent 14 years

Int. Cl. D12—09

U.S. Cl. D14—3

Fig. 1.

Fig. 2.

Fig. 3.

Fig. 4.

Fig. 5.

FIG. 1 is a side elevational view of a fire truck embodying my new design;

FIG. 2 is a top plan view thereof;

FIG. 3 is an elevational view showing the side thereof opposite that shown in FIG. 1;

FIG. 4 is a front view thereof; and

FIG. 5 is a rear view thereof, the engine and transmission being shown in broken lines for illustrative purposes only.

I claim:

The ornamental design for a fire truck, as shown and described.
